(57) **CLAIM**

I claim the ornamental design for double compound aviation snips, as shown and described.

DESCRIPTION

FIG. 1 is a front elevational view of a first embodiment of double compound aviation snips of the present application;

FIG. 2 is a rear elevational view of the first embodiment of the double compound aviation snips;
FIG. 3 is a right side elevational view of the first embodiment of the double compound aviation snips;
FIG. 4 is a left side elevational view of the first embodiment of the double compound aviation snips;
FIG. 5 is a top plan view of the first embodiment of the double compound aviation snips;
FIG. 6 is a bottom plan view of the first embodiment of the double compound aviation snips;
FIG. 7 is a front elevational view of a second embodiment of double compound aviation snips of the present application;
FIG. 8 is a rear elevational view of the second embodiment of the double compound aviation snips;
FIG. 9 is a right side elevational view of the second embodiment of the double compound aviation snips;
FIG. 10 is a left side elevational view of the second embodiment of the double compound aviation snips;
FIG. 11 is a top plan view of the second embodiment of the double compound aviation snips;
FIG. 12 is a bottom plan view of the second embodiment of the double compound aviation snips;
FIG. 13 is a front elevational view of a third embodiment of double compound aviation snips of the present application;
FIG. 14 is a rear elevational view of the third embodiment of the double compound aviation snips;
FIG. 15 is a right side elevational view of the third embodiment of the double compound aviation snips;
FIG. 16 is a left side elevational view of the third embodiment of the double compound aviation snips;
FIG. 17 is a top plan view of the third embodiment of the double compound aviation snips; and,
FIG. 18 is a bottom plan view of the third embodiment of the double compound aviation snips.
The broken lines in the drawings depict portions of the double compound aviation snips that form no part of the claimed design.
